UNITED STATES PATENT OFFICE.

SUMTER B. BATTEY, OF NEW YORK, N. Y.

HAIR WAVING OR CURLING DEVICE.

Application filed November 4, 1926. Serial No. 146,201.

This invention relates to improvements in marcelling or hair curling and hair waving devices which effect the results desired either with or without the use of heat.

5 One object of this invention is to provide an improved device whereby the hair may be more quickly and easily disposed upon suitable forms for imparting desired confirmations thereto, such as waves or curls.

10 A further object is to provide improved means for applying tension to the hair whereby it may be more effectively acted upon by the forms upon which it is wound or otherwise disposed and without likelihood of 15 transmitting any of such tension to the scalp.

The invention further contemplates novel means for simultaneously operating a plurality of forming instruments whereby a 20 number of waves or other desired configuration of the hair may be simultaneously produced by the manipulation of a single actuating element.

Another object of the invention is to provide means for locking the forming instruments in adjusted position whereby the hair 25 may be continuously subjected to treatment for any desired period. The invention also provides improved means for fastening the hair to the forming instruments.

30 The invention also aims to provide forming instruments of improved design whereby waves of more beautiful form may be imparted to the hair.

Further objects of the invention will be 35 apparent from the following detailed description, throughout which reference is had to the accompanying drawings, in which

Figure 1 is a perspective view of one embodiment of the invention which carries a 40 plurality of wave or curl forming instruments.

Fig. 2 is a fragmentary front elevation of the frame of the device shown in Fig. 1.

Fig. 3 is a cross-section of the device shown 45 in Fig. 1 taken along the lines III—III.

Figs. 4 and 5 show diagrammatically the disposition of the hair on the device before and after tightening it around the forms.

Figs. 6 and 7 show diagrammatically another and slightly modified arrangement whereby the device of Fig. 1 can be made to produce waves which are not parallel to each other.

Figs. 8 and 9 are front and side views of 50 the device shown in Figure 1 indicating two

possible methods of applying the device to the head whereby waves may be produced at the side or back. In Fig. 8 the frame is placed across the head, and in Fig. 9 the frame of the device extends from front to rear.

Figs. 10 and 10^a are respectively a fragmentary front elevation and longitudinal cross-section of a modified form of the device shown in Figure 1 whereby the rotatable forms which are geared together may be adjusted along the frame to produce waves in the hair at any desired interval.

Fig. 11 is a perspective view of a modified form of the invention having only a single 70 rotatable form.

Fig. 11^a is a modified form corresponding to the device shown in Fig. 11 but having two rotatable elements instead of one.

Fig. 12 is a cross-section taken along the 75 lines XII—XII of Fig. 11.

Fig. 13 is a fragmentary elevation showing the details of the secondary form locking device employed in the construction shown in Fig. 11.

Fig. 14 is an elevation of a further modification of the invention having only a single wave-forming instrument, the instrument, however, embodying the special form of comb utilized in the larger device shown in Fig. 1 85 whereby a serpentine curve may be imparted to the hair.

Fig. 15 is a plan view of the device shown in Fig. 14, along section line XV—XV.

Fig. 16 is a perspective view of one type of 90 hair waving form which may be used in the device shown in Fig. 1, for example, this form being heated by the circulation of hot fluid therethrough.

Fig. 17 is a modified hair waving form in 95 which heat is developed electrically.

The device in its preferred embodiment, as shown in Fig. 1, comprises an arcuate frame having front and rear plate-like members 2 which are connected at their ends by suitable 100 cross-pieces 3 and at points intermediate their ends, if desired. As this frame preferably rests directly upon the head of the person whose hair is being waved, the inner surfaces thereof are preferably provided with cushioning material, such as soft rubber, leather or the like in the form of bands or ribbons 4. At intervals between the front and rear members of the frame are disposed rotatable forms 105 A, A', A'', etc., the number of such forms de- 110

pending upon the number of waves or curls that are to be made in a given length of hair. At either end of the frame an independently rotatable form B is preferably employed.

- 5 This end form may be either of the type shown in Fig. 11 or Fig. 14, the latter being employed for the purpose of imparting a wave of special shape at or near the ends of the strand of hair being treated. This latter 70
10 form is provided with comb-like teeth of novel design and will hereinafter be particularly described.

Preferably between each pair of forms B—A, A—A', A—A'', etc., wave-measuring 15 elements C, C', etc. are employed for the purpose of insuring the presence of the right amount of loose or slack hair between the adjacent rotatable forms to permit of the desired length of hair to be wrapped around 20 each form during the actual curling or waving operation. During such operation the aforesaid wave-measuring elements C, C', etc., are either removed entirely from the frame or moved into a position in which the 25 slack which they originally measured is left free to be wrapped about the rotatable forms. The function of the said measuring elements will be readily understood from a consideration of the diagrams in Figs. 4 and 5.
30 The hair is first combed out into straight strands and laid on top of the measuring elements C', C'', etc. and is gripped between the upper and lower halves of the rotatable forms A, A', A'', etc. The measuring elements shown in cross-section in Fig. 4 comprise simple straight pins extending between the front and rear frame members. After the hair is set up in the device as shown in Fig. 4, the measuring pins are removed by 35
40 simply drawing them endwise out of the frame. Thus, between each of the rotatable forms A, A', etc. there is left a measured length of hair sufficient when wound upon the forms to produce a wave of the desired 45 shape and dimensions. As shown in Fig. 5, when the forms are rotated the slack hair which remained between them after the measuring pins have been removed, entirely disappears, being now taken up on the forms 50 themselves. If the forms are rotated through only a half turn the hair is disposed, as shown, in a series of S turns.

It will be readily understood that after rotating the forms as shown in Fig. 5 to a position 55 in which the loose hair between them has disappeared, any further rotation will set up a stress in the hair which tends to cause it to quickly assume the curvature determined by the shape of said forms, and I have found that this stress, while not in any way injurious to the hair, aids very materially in rendering the wave imparted thereto more lasting and permanent. The set of the hair in the desired wave may obviously be aided 60
65 by any of the methods known in the hair wav-

ing art, such as by the application of heat after moistening the hair or by drying out volatile substances with which the hair is previously impregnated. It will be understood, of course, that the forms A, A', etc. 70 may be of any desired shape and may be rotated to any desired extent, it being possible to wind the hair about such forms one or more times by simply rotating them beyond the position shown in Fig. 5. 75

In Figs. 6 and 7 there is diagrammatically illustrated the use of a wave-measuring element which is adapted to produce a wave which is longer toward the front of the head than at the rear. This is frequently desirable as such waves are usually considered more beautiful than those which have precisely parallel crests. One type of measuring element suitable for this purpose is shown in perspective in Fig. 1 and designated by the 80 numeral 5. The said element comprises preferably a sheet metal member bent around a measuring pin C' so that it frictionally grips said pin. Thus disposed, the element has two triangular or tapered surfaces 6 and 7 substantially at right angles to each other, the edges of which are curled over to provide a smooth and rounding surface for the hair to rest upon. The two triangular extensions of the special measuring element 5 will hereinafter be referred to as wings, the larger wing 6 being called the measuring wing and the smaller wing 7 the forming wing. It will be furthermore noted that when a measuring device employing tapered wings is 85 used, the rotatable forms A, A', etc. are also 90 preferably tapered, as shown in Fig. 1.

The operation of the special measuring element 5 will now be explained with reference to the diagrams in Figs. 6 and 7. In Fig. 6 105 the element 5 is shown in the measuring position, the tapered measuring wing 6 being operative to hold up and measure a wave of slack hair, which, because of the shape and disposition of the wing, will be a considerably longer wave at the front than at the rear end. The shape of the wave at the front end of the wing is indicated in full lines while the shape of the wave at the rear end of the measuring wing is indicated in dotted lines. 110
115

After the slack hair necessary to form the desired wave has been measured out, the wing 6 of the element 5 is swung into the horizontal position, as shown in Fig. 7, thus moving the forming wing 7 into the active vertical position. If the forms A, A' be now rotated, the hair clamped between them will be wound up and drawn against the upper surface of the tapered forming wing 7. This forming wing then imparts an additional curvature to the hair in the part of the wave between the rotatable forms A, A' which is not present in the wave produced as indicated in Fig. 5. At the same time the slope of the forming wing from front to rear results in a wave 120
125
130

which is longer between crests at one end than it is at the other, and permits of the equal stressing of the hair over the entire length of the forms.

5 It is obvious that the device shown in Fig. 1 may be operated with either the straight or the tapered wave-measuring elements above described, these elements being readily interchangeable.

10 The rotatable forms A, A', A'', etc., are preferably made in two parts as indicated in enlarged cross-section in Fig. 4. The upper half of each form may be hinged to the lower half, as shown in Fig. 3. After the hair is 15 laid over the lower half 10 of each form, the upper half 11 is swung down and locked tightly against the hair by any suitable means. A catch comprising a split or notched collar 12 mounted rigidly on frame 20 2 and surrounded by a rotatable split or notched sleeve 14 has been found satisfactory. The said collar 12 is adapted to receive both halves of form A. If the sleeve 14 be rotated to bring its opening 15 into alignment with 25 the opening 16 of collar 12, the hinged half 11 of form A will be released by turning the form until the movable half thereof registers with the aforesaid notches 12, 14. The two halves of the form are locked together by 30 swinging part 11 into the central opening of the collar and turning the locking sleeve 14 so as to throw the notches out of registration.

An important feature of the present invention is the means for simultaneously imparting rotation to a plurality of forms by the actuation of a single key or other manually rotatable element. The simultaneous rotation of the forms is accomplished in the following manner. It will be seen, referring to 40 Fig. 1, that at the end of the forms A, A', etc., driving gears 20 are provided, the said driving gears being interconnected by intermediate pinions 21. Through this gear train any rotation imparted to the form A'', for 45 example, will produce a like rotation in the forms A and A'. The forms on the right hand side of the device may be geared to the forms on the left, as above described, or they may be separately controlled, as desired. It 50 is generally desired when the device is utilized to wave both sides of the head to have the forms on opposite sides of the frame, oppositely rotated. For certain types of waving it may be desired to have all the forms alternately rotated clockwise and counter-clockwise. This is readily accomplished by 55 substituting driving gears of larger diameter than those illustrated so that the driving gears mesh directly one with another.

60 Certain of the driving gears 20 are preferably connected to their respective forms through ratchet means so that such forms are susceptible of independent adjustment in addition to the rotation commonly imparted 65 by the action of the gear train. It will be

evident that if three forms are connected together for common rotation, the tightening of the hair between any two of the forms will prevent further rotation of the third form, which may not have taken up all the slack 70 hair between it and the second form. To take up such slack and properly stress the hair over the third form, such form must be further rotated and this is accomplished by turning the squared end 22 of the form 75 A, for example, by means of a key. The spring-pressed pawl 23 carried by driving gear 20 permits free rotation of the ratchet wheel 24 in a counter-clockwise, i. e. the direction in which the left hand forms are 80 preferably rotated to tighten the hair. The said ratchet wheel is fixedly mounted on the rotatable form, while the driving gear 20 is only rotatively connected to the form 85 through the ratchet device.

Pawl 23 is normally maintained in engagement with the ratchet wheel by means of a spring 25 but may be manually released by pressing the finger piece 26 formed on the end remote from the ratchet and on the opposite side of the pawl pivot 27. This may be necessary where it is desired to relieve the tension on the hair between adjacent forms without releasing all of the forms.

To maintain the several forms in any desired adjustment, locking means are provided. It is obvious that a single locking device, whereby the rotation of any one of the forms A, A', etc. may be prevented, will effectively prevent the rotation of all the 100 forms connected by the aforesaid gear train. However, in the preferred embodiment of the invention, independent locking means are provided to prevent the rotation of each form individually. This permits of releasing any 105 of the forms without releasing the others. Such locking means may comprise a pawl and ratchet device interposed between a form and the frame, or it may be constructed as a tapered pin lock 19 similar to the tapered peg 110 used in violins to adjust the tension of the strings.

Locking pawls 28 may be mounted on the frame adjacent each of the ratchet wheels 24, which, as hereinbefore described, are in turn fixedly mounted on the rotatable forms. These pawls may be engaged and disengaged by manipulating pawl-actuating finger pieces 29 which are preferably formed integrally with the pawl arms.

115 Obviously the forms may all be provided with taper locks similar to the lock 19 shown for the special form B at the end of the frame instead of the ratchet lock above described. Such a lock comprises simply a 120 slightly tapered or conical form end 30, fitting into a conical recess 31 in a rear adjustable slide 59 carried by the frame. This slide will hereinafter be described in detail. The rotatable form has just sufficient axial 125 130

play to permit of engaging and disengaging the taper lock, the operator having only to apply a slight rearward thrust to securely fasten the form against rotation. A slight forward movement of the form releases it for free rotation. The details of such a conical lock are shown in Fig. 3.

For the purpose of producing waves of a more permanent nature the application of heat to the hair after it has been properly disposed on the forms is desirable. This may be accomplished in a variety of ways, as by the use of hot air, steam, hot water or electric heating elements. In Fig. 16 there is shown means whereby steam or hot water or other heated fluid may be circulated through the forms. In this case the forms may be made hollow and provided with suitable connections whereby fluid may be introduced and drawn off. Heated fluid may be circulated through the forms by any desired method, such as by pumping, gravity or by a thermosiphon system. The hollow forms A may be provided with nipples 33, 34, over which flexible tubing 35, 36 may be slipped, the tubing being connected respectively to the source of heated fluid and to any suitable exhaust. Valves 37, 38 are preferably included in the intake and exhaust lines to regulate the flow of fluid for controlling the temperature of the forms and also to permit of disconnecting the tubing therefrom without spilling or wasting the fluid medium. It is apparent that two or more forms may be connected together in series or each form may be independently supplied from the common source.

In Fig. 17 there is shown an electrically heated form A_2 which may be used instead of the form above described. This modification comprises a two-part tubular form similar in outward appearance to the forms A, A', etc. in Fig. 1. The two parts 40, 41 are preferably heated by two resistance wire heating elements 42, 43 confined within the hollow interior of the form parts. The heating wires must be electrically insulated from the form, and this may be accomplished by surrounding the wires with mica or other suitable electrical non-conducting material. At the hinged end of the form a rotary contact switch 45 may electrically connect the heating elements 43, 43, when the divided form is closed, while at the opposite end, feed wires 44, 45 are connected by a double pronged plug 46. By such arrangement the heater elements in any given form are connected in series. When a plurality of forms are used, as shown in Fig. 1, they are preferably connected in parallel to the current supply.

It will be clear that external heat may be applied to the hair after it has been disposed on the forms independently of any form heating means. A convenient means for dry-

ing out moisture with which the hair on the forms has been dampened, is the usual electric hot air blower.

A feature of adjustability whereby the forms A, A', A'', etc., may be variably positioned in the frame 2 is afforded by the provision of a plurality of bearing holes 50 closely spaced along the forward and rear frame members. The bearing holes are all like those in which the forms are shown resting in Fig. 1. To permit of the ready transfer of forms from one bearing to another the front and rear frame members are preferably split along the line of centers of the said bearing holes 50 into upper and lower frame segments 51 and 52. The upper segment 51 is centrally divided into independent frame elements which at their remote ends are hinged by hinges 51' to the lower continuous frame segment 52. The adjacent ends of these upper frame elements 51 are provided with snap latches 53 which automatically lock the said elements to the lower frame segment 52. As the latches are alike, only one will be described. The latch arm 54 is pivoted to the upper frame element, and under the action of a spring 55 engages a pin 56 fixed in the lower frame segment 52. A detent 57 engages latch arm 54 to hold it in proper position against the action of the spring so that the latch will automatically snap over the pin when the frame is closed.

If it is desired to change the spacing of the forms A, A', A'', etc., the latches 53 are released and the upper frame elements 51 swung upward. This releases the said forms which may then be shifted to other bearing holes. Intermediate gears 21 of suitable diameter to connect the driving gears carried by the forms, are set in the frame, the intermediate gears being carried on studs 58 which fit snugly in bearing holes 50. If the forms are to be widely separated, a plurality of intermediate gears may be interposed between the driving gears on the end of the form shafts. If an odd number of intermediate gears are so used the forms will be rotated in the same direction, or if an even number of intermediate gears are used, the forms will be oppositely rotated. Obviously this feature of adjustability permits of varying the number of forms in the frame from a single pair to any required number, depending upon the length of hair and desired spacing of waves.

A feature of continuous adjustability for the end forms B is provided by the slide mounting 59 which may be moved along the frame by any suitable adjusting means. A rack 59^a and pinion 59^b may be employed for this purpose, one at each end of the form. The slide 59 is guided between guides 59^c formed on the frame and the frame is slotted at 59^c to permit movement of the form over the extent of adjustability provided by the

rack and pinion. The pinions 59^b are actuated by turning the knobs 59^d projecting therefrom. The position of the slide 59 along the frame may be fixed by any suitable means. 5 A satisfactory device for accomplishing this result comprising a thumb nut 59^e which engages the threaded end of the shaft of pinion 59^b and draws said pinion tightly against the frame, thus locking the pinion against 10 rotation. The rear slide 59 carries the rear element of the comb clutch hereinbefore referred to.

The above described slide means for adjusting the end forms B may be used in two ways. 15 The forms may be shifted along the frame to produce various spacing of the waves between adjacent forms, the hair being tensioned between such forms by the rotation of the form; or the hair may be tensioned between and around the forms by the bodily movement of the end form under the action of the rack and pinion 59^a, 59^b, the hair being first caught on the forms. It is obvious that the hair may be stressed just as effectively by bodily shifting one form with respect to another as by rotating one or both of such forms.

An added advantage of the slidable form B which may be shifted sideways is that the hair at every point along the bar may be stressed with greater uniformity because of the fact that the two ends of the bar are separately controlled and should the hair become tight at one end of the bar before the hair at the other end is under tension, the latter end is simply given a slight additional movement.

A modification of the movable form arrangement above described is shown in Fig. 10. This construction permits of the continuous adjustment of the space between forms while the gears of the train remain in mesh. The forms A, A' are guided in frame slots 60 and are connected together preferably at both ends by means of links 61, 62. These links at their lower ends surround the form shafts and connect said shafts to the hub 63 of the floating intermediate gear 64. While the form shafts and also the hub of the intermediate gear are free to rotate within the bearings provided by said links, the two driving gears are nevertheless constrained to maintain a uniform center distance from the intermediate gear whereby the said gears will always be maintained in perfect mesh regardless of the position of the driving gears along the slot 60. If the driving gears be spread apart to the maximum distance, the intermediate gear will be lowered until its axis lies in a line connecting the centers of the driving gears. The gears may be moved into any desired position and there locked by means of adjustable distance pieces 65 and 66. The distance pieces 65, 66 comprise respectively an adjustable connecting link between

the shafts of the forms A, A', and an adjustable link 66 between the shaft of form A' and the frame 2. The link 65 may consist of two overlapping slotted strips having a thumb screw 67 which clamps the two pieces together in any desired adjustment. The link 66 is similarly slotted and is positioned with respect to the frame by means of a thumb screw 68 which clamps the link in any desired adjustment to the frame. It will be obvious that any number of forms greater than two may be progressively connected by the adjustable link mechanism above described.

A modified form of the present invention is illustrated in Figs. 11, 12 and 13. This modified construction, while embodying a number of the features of the larger device shown in Fig. 1, is relatively simple, only a single rotatable form being employed. The device may, however, provide the facility for tensioning the hair between two parallel members through the action of said rotatable form, and also incorporates means for maintaining this tension for any desired period. The device comprises a C frame 70 which may be made of sheet metal or other rigid material, such as hard rubber or bakelite. The forward downwardly-extending arm in the perspective view of Fig. 11 is bent to form a bearing 71 for the rotatable form A. The end of this frame arm is not brought completely around the form shaft but is left open and swung outwards, as indicated at 75, to provide what may be termed a spring clip. This construction permits of the ready insertion and removal of the rotatable form by simply snapping it into the clip or springing it out. The opposite downwardly projecting arm 73 of the C frame carries at its end a tapered or conical bearing 74 in which the tapered end 75 of the rotatable form is inserted. By this construction there is provided a taper lock similar in principle to the lock shown for form B in Fig. 1.

A notched sleeve and collar lock 76 and 77 is provided adjacent the aforesaid tapered end bearing on the frame identical in construction with the lock 12, 14 shown in Fig. 1. The purpose of this lock is to maintain the upper and lower parts 78 and 79 of the rotatable form close together where they exert a clamping action on the hair which is disposed between them. In the present instance the upper half of the form, instead of being hinged to the lower half, is formed integrally therewith, and is preferably designed to have sufficient resiliency to normally insure its standing away from the lower part far enough to permit the placing of the strand of hair in the form simply by sliding the open form end endwise through the hair. A collar 80 surrounding the form shaft prevents the form from shifting endwise sufficiently to prevent the upper half 78 of the divided part thereof to escape from the retaining sleeve 130.

77 except when such escape is permitted by the registration of the notches in the sleeve and collar locking device above described.

As an equivalent of a second rotatable form 5 such as form A' in Fig. 1, the present device is provided with a simple bar clamp 81 pivoted at one end to the upper part of the frame as by means of a loose rivet 82, the other end of the bar clamp 81 swinging under a catch 10 83 fastened to the rear vertical frame part 73. Both the frame and bar are preferably somewhat resilient so that when a strand of hair is placed between the top frame member and the bar 81, the bar may be snapped into 15 the catch 83, as shown in Fig. 11, and by this means apply to the hair a yielding grip which will be sufficiently effective to permit of the tensioning of the hair between the upper part of the frame and the rotatable form 20 A. This tensioning is effected, as previously described, by the rotation of the form in either direction. When sufficient tension has been created the form is locked by a slight axial rearward thrust which engages the 25 cone clutch 74, 75.

A secondary form D may, if desired, be interposed between the bar clamp and the rotatable form A. This form is shaped to provide a convex surface toward the hair 30 wound on the said rotatable form and is vertically adjustable along the arms 70, 73 of the frame. The form may be made of a single piece of sheet material doubled together, as shown in Fig. 11, guide strips 85 at the 35 upper edges extending over the frame members to secure the secondary form in the frame. Within the secondary form a ratchet 86 is pivoted at either end, these ratchets engaging teeth 87 cut in the vertical frame members. The ratchets are engaged in the 40 teeth by the action of springs 88 and may be disengaged by manually depressing the finger piece 89 formed integrally with the ratchet lever. By this construction a secondary form 45 is provided, which, when the hair is tightly stretched over it, the hair being tensioned between the rotatable form and the bar clamp at the top of the frame, will impart an additional curve to the hair. The said secondary 50 form also may be pressed downwardly into tight contact with the hair wound about the form A and there automatically locked by the ratchets 89. By this means the hair will be even more effectively set around the form, 55 being held in the desired position by tension between the bar clamp and the form and also by compression set up by the action of the secondary form D. When used in this manner the secondary form comprises an effective 60 adjustable clamping means for securing the hair which has been wound upon the form A, and for certain purposes such as making a tight wave close to the head the form D can be used independently of the bar clamp 81, 65 the hair passing directly from the form A

upon which it is clamped by form D to the scalp.

It is often desirable to use a single rotatable form as described above, and a satisfactory wave may be locally produced at any desired 70 part of the head by the use of the device in its simplest embodiment comprising a rotatable form in a frame, and a cone clutch to prevent relative rotation of the form and frame. The device may be constructed as shown in 75 Fig. 11 but without the bar clamp 81 or the secondary form D. In such a device the hair is simply wound around the form until the frame is drawn by such winding action against the scalp. If the form is then 80 clutched to the frame, the hair can not unwind and will be subjected to the tension with which the form is drawn against the head. In this simple form the divided form having 85 the upper and lower elements formed integrally is preferably employed. Such divided form tends, when the free end is released, to spread apart so that the free half of the form, i. e., the half not held in the frame bearing may be readily slipped under or 90 through the hair to pick up a tress of the desired size.

In Fig. 11^a there is shown a somewhat modified form of device corresponding generally to the device shown in Fig. 11 but having 95 two rotatable divided rods or forms A, instead of one. The rotatable divided forms and locking and clutch means therefor are identical with the form A and its corresponding appurtenances shown in Fig. 11. The 100 distinguishing feature of the device of Fig. 11^a is the simple rectangular frame F carrying the four resilient arms F' which provide bearings for the two forms A'. The resiliency of these arms, which preferably are 105 formed integrally with the frame, elastically stress the hair tensioned between the forms and insure tension on the hair all along the forms.

In Figs. 14 and 15 there is illustrated a 110 still further modified form of the invention in which a simple C frame 90 carries a rotatable form 91 of special design. This form is characterized by the peculiar comb arrangement which imparts a wave of unusual 115 form to the hair. This wave may be termed a serpentine wave and differs from the ordinary simple wave in that it has a wave formation in both horizontal and vertical planes. The rotatable comb-like form 91 carries relatively broad triangular-shaped teeth 92, but these teeth, instead of being disposed with their broad surfaces lying in planes perpendicular to the axis of the comb, are set at an angle. This is perhaps best illustrated in 120 Fig. 15, which shows the teeth in cross-section along section line XV—XV of Fig. 14. One strand of hair is shown in dotted lines to the left in this figure and illustrating the action 125 of the angularly disposed teeth. It will be 130

observed that the strand of hair which ordinarily would be wound continuously in a circle as the form is rotated, is now, by the action of the angular teeth, caused to be deflected at each revolution of the form into the next succeeding tooth space, a strand of hair entering upon the first revolution at the point marked *e* and being deflected by the teeth to a point on the form, where, upon the next succeeding revolution, it will enter the tooth at the point marked *f*. It will be understood that normally strands of hair would be disposed between practically all the comb teeth, and as a consequence, a strand entering originally at, let us say, the point marked *g*, will, at the beginning of the second revolution of the form, be deposited on top of the strand *e*. As a result of this action the hair not only assumes the curvature of the round body of the form, but also a transverse wave is effected, as explained by the action of the angularly disposed teeth.

It is possible to place the teeth of comb 91 sufficiently close together so that the hair will be effectively picked up and held on the form in order that it may be tightly wound thereon without the use of any clamping means whatever. However, in the preferred construction illustrated the teeth are rather widely spaced and a pivoted, semi-cylindrical clamp 93 is provided to initially attach the hair to the rotatable form. This clamp may resemble the usual curling iron clamp, a catch 94, however, being provided to lock the clamp 93 securely against the form 91 whereby to more effectually grip the hair disposed therebetween. The form is rotated by turning a thumb screw 95 and is locked against rotation by a conical locking device 96 precisely similar in principle to the conical locking device described in connection with the devices of Figs. 1 and 11.

The operation of the devices hereinbefore described has been made clear in the course of such description. In the preferred embodiment of the invention illustrated in Fig. 1, the operation may be summarized as follows: The device is set up with the desired number of forms of wave-measuring elements according to the length of hair to be treated and the type of wave required. The divided forms are unlocked and the upper half of each form swung into a vertical position. The hair is then preferably combed straight either towards the sides of the head or from the forehead backwards, depending upon whether the waves are to be produced at the sides of the head or at the back. The device is then placed upon the head either as shown in Fig. 8 or Fig. 9, and the hair laid over the top of the measuring elements C, C', C'', etc. The upper half of the divided forms are then swung down and locked in the retaining collars 12, commencing preferably with the

form nearest the roots of the hair and proceeding progressively to the end of the frame. The hair is thus locked in the rotatable forms, as shown diagrammatically in Figs. 4 or 6.

If a simple measuring pin is used, as shown in the former figure, these pins are then withdrawn endwise from the frame, or, if a wave-measuring and secondary form device 6, 7 is employed, as shown in the latter figure, the device is rotated to throw the wave-measuring wing 6 into inoperative position. The forms are then rotated preferably simultaneously and in the same direction by applying a key or other turning instrument to the square end of form shaft A'', for example, the gear train transmitting the movement of form A'' to forms A' and A. Hair when wound about the forms appears either as shown in Figs. 5 or 7. To insure the maximum desired tension between each pair of forms, the forms may be independently tightened, the ratchet devices hereinbefore described permitting of such independent rotation of the forms. A special form B is provided for the ends of the hair. This form is preferably of comb-like construction, the form shown in Figs. 14 and 15 being particularly suitable for the purpose. The teeth may be sufficiently close together so that the ends of the hair will be caught and frictionally held in the comb without other clamping means, and the form is then rotated to wind up all the slack hair between forms A and B. The end form B is then tightened to produce the desired stress in the hair and locked in such adjusted position by a slight endwise movement which engages the comb clutch at the end of the form. The hair is then permitted to set for a time, and this setting or fixing of the wave may be rendered more effective by the use of heat applied either externally by means of a draft of hot air, for example, or internally by the use of heated forms such as are illustrated in Figs. 16 and 17. Obviously both methods of applying heat may be used simultaneously.

The device shown in Fig. 1 is provided with a cover plate E which fits over the end pieces of the frame and completely encloses the forms. This plate may be made of suitable insulating material whereby the heat generated within the heated forms may be retained about the hair.

The above described device involves a radical departure from the ordinary hair waving methods. In this device the wave is imparted to the hair over forms of the correct shape to directly impart the desired curvature to the hair. The spacing of the forms determines with mathematical certainty the length and shape of the wave produced, whereas, according to heretofore known methods, the waves are produced by twisting the strands of hair spirally around a rod or tube, and consequent-

ly the length and form of wave is at best a matter of chance, considerable skill being required to produce waves at different parts of the head which correspond at all times closely in length and shape. The present device furthermore permits of the uniform stressing of the hair disposed between the rotatable forms, it being possible to apply such stress to the entire length of a strand of hair, whereas in methods hitherto known wherein the entire length of hair is wrapped around a rod, if stress is applied at all in an effort to tension the hair, this stress is localized in the hair at the ends of the rod around which it is wound, the frictional effect of the hair wound many times about the rod effectively preventing the transmission of any appreciable stress to the hair midway between the ends.

While various embodiments and modifications of the invention have been hereinbefore described, it is to be understood that the invention is not limited thereto but may be otherwise variously modified and embodied without departing from the spirit thereof, as set forth in the following claims.

What I claim is:

1. A hair waving or curling device comprising a frame, a rotatable form supported thereby, said form being adapted to wind up and tension a strand of hair, means for locking the form against rotation relative to the frame, and supporting means carried by the frame and engaging a strand of hair, said supporting means being adapted to sustain the tensile stress applied to the hair by said rotatable form whereby the hair may be tensioned without imparting pull to the scalp.

2. The device according to claim 1, further characterized in that a secondary form is interposed between said rotatable form and said supporting means, said secondary form being carried by said frame in a position which deflects the hair tensioned between the rotatable form and the said supporting means whereby an additional wave is imparted to the hair.

3. A hair waving or curling device comprising a rotatable form upon which a flattened strand of hair may be wound, a frame externally embracing and rotatively supporting said form at points on either side of the portion of the form on which the hair may be wound, and clamping means mounted on said frame and adapted to grip a strand of hair whereby the said strand when so gripped may be tensioned around the form by rotating the latter relatively to the frame.

4. A hair waving device comprising a frame, two divided hair engaging forms carried by said frame and means for producing a rotation of at least one of said forms relative to said frame whereby tension may be applied to hair disposed between said forms.

5. A hair waving device including a frame, two rotatable hair engaging forms spaced

apart on said frame, and gears connecting said forms for simultaneous rotation whereby to wind the strand of hair about each form and tension the hair around and between said forms.

6. A hair waving device including a frame, two rotatable hair engaging forms spaced apart on said frame, gears rotatively connecting said forms and locking means adapted to prevent the rotation of the forms whereby when the hair is brought to the desired tension between the forms, such tension may be continuously maintained.

7. A hair waving or curling device including a frame, a plurality of rotatable forms along said frame, and a plurality of movable wave-measuring elements adapted in one position to determine the length of slack hair to be left between adjacent forms, and in another position to free such hair so that the slack may be taken up by rotating at least one of the forms.

8. A hair waving or curling device including a frame, a rotatable form, a divided bar at a distance from said form, and wave-measuring means between said form and said bar, the said form, bar, and measuring means being mounted on said frame.

9. A hair waving or curling device including a frame, a rotatable form, a divided bar at a distance from said form, and a wave-measuring and secondary form device adapted in one position to measure the slack hair required to be wound on the said form, and in another position to serve as a secondary form.

10. A hair waving or curling device including a frame, a pair of forms, said frame being adapted to support said forms at various intervals whereby the length of a wave produced by the device may be varied.

11. A hair waving or curling device including a frame, a pair of forms mounted on said frame and a movable wave-measuring and secondary form device interposed between said forms adapted in one position to measure the required slack hair between forms, and in another position to serve as a secondary form.

12. A hair waving or curling device including a frame having a plurality of form bearings, said frame being divided along the centers of said form bearings whereby the frame parts may be separated to permit of the insertion or removal of forms.

13. A hair waving or curling device according to claim 12, further characterized in that said frame is also provided with a plurality of bearing holes adapted to receive measuring pins at points intermediate adjacent forms.

14. A hair waving or curling device including a frame, a plurality of rotatable forms, gears connecting said forms for common rotation, at least one of said gears being

- releasably connected to the form which it drives whereby the form so connected may be rotated either commonly with the other forms or independently thereof.
- 5 15. A hair waving or curling device including a hollow form about which the hair is adapted to be wound and means for producing a flow of heated liquid through said hollow form.
- 0 16. In a hair waving or curling device a rotatable form, a frame within which said form is mounted, said form being divided longitudinally within said frame to receive a flattened sheaf of hair, means to rotate said 15 form to wind said flattened sheaf of hair thereon between said form and said frame, and a cone clutch interposed between said frame and said form whereby the form may be clutched to the frame to prevent relative 20 rotation of said form and frame.
17. In a hair waving or curling device a frame, a form rotatably supported by said frame, said form being at least in part longitudinally divided into two cylindrical halves, 25 said halves mutually co-operating when the form is rotated to impart a substantially smooth S turn to hair placed between said halves.
18. A hair waving or curling device including an external frame, a divided rotatable form mounted in said frame and upon which form a flattened sheaf of hair is adapted to be wound and locking means adapted to prevent rotation of said form with respect 35 to said frame, said locking means comprising a cone clutch, the two elements of which are carried respectively by said frame and said form.
19. A hair waving or curling device including a frame, a rotatable form mounted in said frame and locking means adapted to prevent rotation of said form with respect to said frame, said form having a plurality of comb teeth, said teeth having a transverse cross-section long and comparatively narrow, the 45 said teeth being disposed along the form with their broad sides lying at an angle to a plane perpendicular to the axis of the form.
20. A hair waving or curling device including an external frame, a comb rotatably mounted in said frame and locking means adapted to prevent the rotation of said comb with respect to said frame.
21. A hair waving and curling device including a pair of hair engaging bars, manually operable means to impart movement to at least one of said bars to tension hair disposed between said bars, and means adapted to prevent displacement of said bars whereby 55 to maintain the tension on the hair disposed between them for the desired time.
22. A hair waving or curling device including a frame, a partially divided bar in said frame, said bar being partially divided
- into two co-operating parts between which parts hair may be placed, the said parts constituting an integral divided form around which the hair is wound, and means for locking the said parts together at the separated end of said bar.
23. A hair waving or curling device comprising a slotted form adapted to receive within its slot a broadly flattened sheaf of hair, a frame rotatively supporting said form near both ends of the form, said frame where it is coextensive with the said slot being disposed at a sufficient distance from the slotted form to permit of winding the sheaf of hair upon the form and within the said frame, and means for clutching the said frame and form together.
24. A hair waving or curling device comprising a slotted form adapted to receive within its slot a broadly flattened sheaf of hair, a frame rotatively supporting said form near both ends of the form, said frame where it is coextensive with the said slot being disposed at a sufficient distance from the slotted form to permit of winding the sheaf of hair upon the form and within the said frame, and means adapted to vary the resistance of rotation between said frame and form for clutching the said frame and form together.
25. A hair waving or curling device comprising a unitary slotted form adapted to receive within its slot a broadly flattened sheaf of hair, a frame rotatively supporting said form near both ends of the form, said frame where it is coextensive with the said slot being disposed at a sufficient distance from the slotted form to permit of winding the sheaf of hair upon the form and within the said frame, and means for clutching the said frame and form together.
26. A hair waving or curling device comprising an external frame, a rotatable form mounted in said frame, said form for carrying a flexible tongue, the free end of which is adapted to spring away from the said form to permit of the ready insertion of a sheaf of hair between the said tongue and form.
27. A hair waving or curling device comprising an external frame, a rotatable form mounted in said frame, said form having a resilient hair-engaging tongue, the free end of which is adapted to spring away from the body of the form whereby to provide an open hair-receiving slot along said form.
28. A hair waving or curling device comprising an external frame, a rotatable form mounted in said frame, said form having a resilient tongue between which tongue and form a flattened sheaf of hair is adapted to be retained.
- In witness whereof, I have hereunto signed my name.

SUMTER B. BATTEY.
